LAUNDRY BASKET

Charles F. Molzen, Wooster, Ohio, assignor to Rubbermaid Sales Corp., Wooster, Ohio

Filed Aug. 9, 1972, Ser. No. 278,933

Term of patent 7 years

Int. Cl. D7—05

U.S. Cl. D7—163

FIG. 2

FIG. 3

FIG. 4

FIG. 5

FIG. 1 is a top view elevation of a laundry basket embodying my new design.

FIG. 2 is a sectional view on line 2—2 of FIG. 1.

FIG. 3 is a side elevation thereof, the other side being identical.

FIG. 4 is an end elevation thereof, the other end being identical.

FIG. 5 is a bottom view elevation thereof.

I claim:

The ornamental design for a laundry basket, as shown and described.
